UNITED STATES PATENT OFFICE.

WILLIAM LIES, OF BROOKLYN, NEW YORK, ASSIGNOR TO GREENPOINT METALLIC BED COMPANY, OF BROOKLYN, NEW YORK, A FIRM COMPOSED OF DAVID FRANK AND WILLIAM LIES, BOTH OF BROOKLYN, NEW YORK, AND JOHN TROUNSTINE, OF NEW YORK, N. Y.

DESIGN FOR A CORNER-POST FOR METAL BEDSTEADS.

46,257.

Specification for Design.

Patented Aug. 11, 1914.

Application filed June 4, 1914. Serial No. 843,105. Term of patent 3½ years.

To all whom it may concern:

Be it known that I, WILLIAM LIES, a citizen of the United States, residing at Brooklyn, in the county of Kings and State of New York, have invented a new, original, and ornamental Design for a Corner-Post for Metal Bedsteads, of which the following is a specification, reference being had to the accompanying drawing, forming a part thereof and presenting a perspective view

of a corner-post for metal bedsteads embodying my design.

I claim:

The ornamental design for a corner post for metal bedsteads, as shown.

WILLIAM LIES.
